UNITED STATES PATENT OFFICE.

FREDRICK S. DICKINSON, OF NEW YORK, N. Y.

DESIGN FOR A TIRE-CASING.

53,066.

Specification for Design.

Patented Mar. 11, 1919.

Application filed December 31, 1918. Serial No. 269,156. Term of patent 14 years.

To all whom it may concern:

Be it known that I, FREDRICK S. DICKINSON, a citizen of the United States, and resident of New York, in the county and State of New York, have invented a new, original, and ornamental Design for Tire-Casings, of which the following is a specification, reference being had to the accompanying drawing, forming part thereof.

Figure 1 is a plan view of a portion of the tread of a tire casing, showing my new design.

Fig. 2 is a cross-section on the line $\alpha-\alpha$, Fig. 1.

The distinguishing and leading features of my design are three parallel ridges, as shown at 1, extending circumferentially at the tread of the tire casing and having a plane surface, the two outer ridges being separated from the intermediate center ridge by grooves or

depressions, as shown at 2, and the surface of said outer ridges being intersected by grooves or depressions, as shown at 3, extending transversely of the ridge and diagonally or at an angle to the longitudinal plane thereof and intersecting the grooves or depressions 2, said grooves or depressions across the respective outer ridges being located in successive series and in parallel relationship, and the grooves or depressions of both the respective outer ridges being located in the same diagonal or angular plane transversely of the tire casing.

I claim:

The ornamental design for a tire casing, as shown and described.

In testimony whereof I have signed the foregoing specification.

FREDRICK S. DICKINSON.
